THOMAS G. SAXTON, OF LEXINGTON, KENTUCKY, ASSIGNOR, BY MESNE ASSIGNMENTS,
TO THE McCASKEY REGISTER COMPANY, (INCORPORATED IN 1914,) OF ALLIANCE,
OHIO, A CORPORATION OF OHIO.

CLAMP DEVICE.

1,122,312.

Specification of Letters Patent. Patented Dec. 29, 1914.

Application filed January 29, 1910. Serial No. 540,903.

To all whom it may concern:

Be it known that I, THOMAS G. SAXTON, a citizen of the United States, residing at Lexington, in the county of Fayette and State of Kentucky, have invented certain new and useful Improvements in and Relating to Clamp Devices, of which the following is a specification.

This invention relates to devices or means for securing articles, such as papers or paper slips upon or against a support or back.

For the purpose of illustration, I have, in the accompanying drawings, shown and herein described one form of device embodying my invention.

Figure 1 is a perspective view of a portion of a support or back showing a clamping or slip carrying device, embodying my invention, secured thereto. Fig. 2 is a longitudinal section of the support and the clamping device and the index or name-carrying plate. Fig. 3 is a perspective view of the clamp device and display plate, detached. Fig. 4 is a transverse section on the line 4-4 of Fig. 2. Fig. 5 is a perspective view of a portion of the support or back showing the attaching means for the clamp carried thereby. Fig. 6 is a section 30 through the strap and spring clamp in Fig. 1.

In the drawing, 1 indicates a suitable support or back adapted to support, on at least one of its faces, articles, as for instance, paper slips. The support or back is preferably formed from sheet metal, in order to reduce the cost of materials and labor.

1^a indicates a strap carried by the support or back 1. This strap 1^a is preferably formed by cutting or slitting the support or back 1 on two transverse lines parallel to each other and then pressing or elevating the metal between the two slits or cuts outwardly on that face of the leaf to which the clamping device is to be secured, as clearly shown in Figs. 5 and 6.

2 indicates a clamping device preferably formed from resilient strip metal. The lower or support engaging end of the clamp device 2 is of a size to extend through the elevated strap 1^a and between it and the support 1. The clamping device 2 is preferably curved outwardly and inwardly, in-

termediate its ends, as shown at 2^a, in order that its free or slip engaging end may operate directly against the support or back 1. The clamp 2 is applied to the support or back 1 by sliding the lower end thereof through the strap 1^a far enough so that its outwardly curved portion will rest on or engage the upper edge of the strap 1^a. By this arrangement of the device 2 relative to the strap 1^a, the former will have a relatively large bearing engagement with the support 1. The strap 1^a is bent relative to the support 1 on parallel lines and engages with the opposite parallel edges of the clamping device 2 to maintain the latter in a vertical position at all times.

In the normal operation of the spring clamp in inserting and removing paper clips, it will be seen that the inner face of the strap 1^a will operate as a fulcrum for the clamp 2 so that said strap 1^a will also operate to hold that portion of the clamp 2 which extends through the strap 1^a in close engagement with the support 1. The clamp may be removed by pulling upwardly thereon. By this form of construction the clamp will have no tendency to slip out, and can only be attached and detached by sliding it in a direction substantially parallel with the face of the support 1.

3 indicates interlocking devices arranged between the clamp device 2 and support 1. 85 These devices preferably comprise a projection 3^a carried by one of these parts, preferably the support 1, immediately below and centrally of the strap 1^a, and a recess or opening 3^b formed in the support engaging end of the clamp device 2. The projection 3^a is preferably formed by indenting the metal of the support or back 1 from the opposite face to which the spring clamp is to be secured. These interlocking devices 95 3 permit the ready attachment to and detachment of the clamp device 2 from the support 1, it being understood that each time the device 2 is applied or removed enough force must be used to cause a springing of the metal strip to permit its free end to ride over the projection 3^a. The lower free end of the device 2 is bent outwardly, as shown at 3^c, to facilitate this operation. The interlocking devices 3, in addition to their function of detachably se-

curing the clamping device 2 in position, coöperate with the strap 1^a to prevent angular movement of the device at all times.

4 indicates a display plate carried by the clamp 2, preferably at its upper free end. This display plate is adapted to carry the name, mark, index numeral or similar device for the clamp device. The display plate has its opposite longitudinal edges 10 turned over, as shown at 4^a, to facilitate the attachment of a card carrying a name, distinguishing mark, or indexing numeral. By this construction the card may be slid in endwise and held by the turned over 15 edges 4^a.

4^b indicates a strap carried by the display plate 4. Preferably the strap 4^b is formed by slitting the display plate upon two parallel lines and pressing the metal between the 20 two longitudinal slits or cuts laterally. The display plate 4 may then be slipped over the free or slip engaging end of the clamp 2, the latter extending through the strap and engaging the adjacent face of the plate 4 25 on opposite sides of the strap 4^b.

5 indicates interlocking devices or means interposed between the display plate 4 and the clamp 2. These interlocking devices may comprise a projection 5^a carried by 30 one of these parts, preferably the clamp 2, and a recess or indentation 5^b formed in the other part, the display plate 4. In the form of the invention illustrated the indentation 5^b is preferably formed in the inner surface 35 of the strap 4^b, and the projection 5^a carried by the clamp 2 is arranged to engage therewith when the display plate is mounted in proper position near the free end of the clamp 2. It will thus be seen that the display plate 4 may be readily applied to and 40

removed from the clamp 2, in a manner similar to the operation of applying the clamp device 2 in position.

To those skilled in the art of making devices of the class described, many alterations in construction and widely differing embodiments and applications of my invention will suggest themselves, without departing from the spirit and scope of the claim. My disclosures and the description therein are purely illustrative, and are not intended to be in any sense limiting.

What I claim is:—

In a filing appliance, the combination of a back formed from sheet metal and slotted along two parallel lines to form a strap, the said strap being elevated relative to the back, a clamp device formed from a strip of resilient metal, the upper end of said device being movable toward and from the back and the lower end of the clamp device extending through the strap and having bearing contact with the adjacent face of the back and the strap operating to detachably hold the clamp device in close contact therewith and permitting its attachment to the back and detachment therefrom only when moved in a direction parallel to it and interlocking means between the lower end of the clamp device and the said back coöperating with the strap for engaging the clamp device but permitting disengagement of the device in a direction parallel to the back.

In testimony whereof I affix my signature, 75 in the presence of two witnesses.

THOMAS G. SAXTON.
